DESIGN FOR A SHOE SHINING RACK

Clare P. Bieger, Chagrin Falls, Ohio

Application April 27, 1945, Serial No. 119,255

Term of patent 14 years

(Cl. D9—2)

To all whom it may concern:

Be it known that I, Clare P. Bieger, a citizen of the United States of America, residing at Chagrin Falls, in the county of Cuyahoga and State of Ohio, have invented a new, original, and ornamental Design for a Shoe Shining Rack, of which the following is a specification, reference being had to the accompanying drawing, forming part thereof:

In the drawing, Fig. 1 is a side elevational view of a shoe shining rack embodying my new design; Fig. 2 is a top plan view of the rack, and Fig. 3 is a sectional view taken on the line 3—3 of Fig. 1.

I claim:

The ornamental design for a shoe shining rack, as shown.

CLARE P. BIEGER.
